FLUID PUMP

Abraham Arthur Fink, 1320 Pembroke Lane, Topeka, Kans., and John J. Sandmeyer, Topeka, Kans.; said Sandmeyer assignor to said Fink

Filed Apr. 26, 1963, Ser. No. 275,833
4 Claims. (Cl. 103—44)

This invention relates generally to fluid pumps and, more specifically, to pumping apparatus especially adapted for applications in the medical arts, including the utilization of the apparatus as an artificial heart or as a means for providing the desired fluid flow in regional perfusion.

By way of background, regional perfusion is a technique especially utilized in the treatment of neoplastic lesions, especially those that have become malignant. This technique involves the isolation of the tumor-bearing area and the insertion of an extracorporeal circuit to supply the cancerocidal or other agent. The arteries or veins of the patient in the area under treatment are actually utilized to transmit the agent to the point of application while suitable pumping apparatus in the extracorporeal circuit provides the desired flow of the agent. This allows isolation of the remainder of the body from the toxic agent thus greatly minimizing the possibility of systemic toxicity. It is requisite in this technique, as well as in the utilization of pumping apparatus as an artificial heart, that the fluid pumping mechanism be maintained under the highest sanitary conditions and be capable of precise control by the physician.

It is, therefore, the primary object of this invention to provide a fluid pump especially suitable for use in the aforesaid medical applications, or as an artificial heart.

It is another object of this invention to provide a pump that may easily be maintained sanitary so that the fluid pumped therethrough will not become polluted and thereby render the fluid unfit for injection into the blood supply system of the human body.

It is another object of this invention to provide a pump utilizing an incompressible fluid to collapse and expand a flexible bag which forms the pumping structure of the apparatus, the bag and the conduits leading therefrom being disposable to facilitate the maintenance of the aforesaid sanitary conditions.

It is still another object of this invention to provide apparatus for reciprocating a shaft or stem operably coupled to a pumping mechanism, such apparatus having means for varying the stroke of said shaft or stem.

It is still another object of this invention to provide such variable stroke, reciprocating apparatus having an assembly adapted for reciprocable movement along a rectilinear path of travel and provided with an element having an elongated slot therein, the longitudinal axis of the slot being at an acute angle with respect to said path of travel, the stem or shaft being coupled with the slot by means enabling the portion of the stem coupled with the slot to ride in the slot longitudinally thereof during movement of the element with the assembly, whereby to reciprocate the stem or shaft in directions transversely of the longitudinal axis of the slot.

It is yet another object of this invention to provide means for varying said acute angle to permit the selection of the desired stroke of the stem and further to provide means for maintaining constant the length of said path of travel regardless of the value of said acute angle.

Other objects will become apparent as the detailed description proceeds.

In the drawings:

FIGURE 1 is a perspective view of the present invention with its case in place;

FIG. 2 is a plan view with the case removed, showing

2

the internal structure of the apparatus for driving the pump;

FIG. 3 is a sectional view taken along line 3—3 of FIG. 2 (with the case in place) showing the flexible bag 34 of the pump in its collapsed condition;

FIG. 4 is a detailed view partially in section and partially in elevation of the pump body and its associated components;

FIG. 5 is a fragmentary, sectional view taken along line 3—3 of FIG. 2 showing the flexible bag in its expanded condition;

FIG. 6 is an electrical schematic diagram of the control circuit for the prime mover of the drive apparatus;

FIG. 7 is a schematic diagram showing an alternate 15 form of control circuit; and

FIG. 8 is a schematic diagram showing another alternate 20 control circuit.

Referring to FIG. 1, it may be seen that the instant invention is housed in a case 10. The case 10 has an access 25 door 12 which may be opened to enable the operator to adjust the pumping rate of the device in a manner to be hereinafter described. A window 14 in the case 10 enables the operator to ascertain whether or not the drive mechanism is operating properly, such window containing pointers 16 and 18 for purposes to be hereinafter described. A plurality of teeth or plates 20 project upwardly through the case and form a part of the magnetic circuit of the prime mover of the drive mechanism. A knob 22 enables the control of the voltage supplied to 30 the prime mover. Switch 24 is an On-Off switch.

Referring now to FIGS. 1—5, it may be seen that the pump comprises a hollow body 26 in the form of a rigid, generally hemispherical shell 28 and a flexible wall or diaphragm 30 extending across the edge of the shell. The shell 28 may be transparent so that the operator may 35 check the functioning of the pump. The body 26 may be a one-piece, disposable unit which is discarded after each pumping operation to assure the maintenance of sanitary conditions. Alternatively, the shell 28 and the wall 30 may be separate pieces integrally sealed at the mating flanges formed at the edge of the shell and the periphery of the wall as shown in the figures.

Body 26 is filled with a substantially incompressible liquid 32. Also, a flexible bag 34 is disposed within the body and surrounded by the liquid 32. The liquid completely fills the body exteriorly of the bag, the volume of the liquid being equal to the volume of the body when the wall or diaphragm 30 is fully flexed against the liquid less the volume of the bag 34 when the latter is collapsed under the pressure of the liquid. An inlet tube or conduit 36 and an outlet tube or conduit 38 communicates with the bag 34. Check valve assemblies 40 and 42, respectively, are provided for conduits 36 and 38 and interconnect the conduits with the bag. A pair of tubular projections 44 integral with bag 34 connect with corresponding check valves by surrounding and engaging the lower extremity of the respective check valve assembly to form a tight seal as shown in FIGS. 3 and 5. Conduits 36 and 38 then are similarly affixed to the uppermost portions of the corresponding check valve assemblies. It may be appreciated that the check valves 40 and 42 may be composed of a rubber or plastic material enabling the same to be conveniently cleaned after each operation or disposed of and replaced later when the pump is next used.

A stud 46 extends outwardly from the central portion of wall 30. Stud 46 contains a T-slot 47 therein enabling the same to be connected to a mating tongue 49 on stem 48. Reciprocation of stem 48 causes wall 30 to flex alternatively against and away from liquid 32 to, in turn, collapse and expand bag 34. This action in co-

operation with the check valves 40 and 42 enable the apparatus to function as a pump. It may be appreciated that since liquid 32 is substantially incompressible, the bag 34 will be forced to collapse under the pressure of the liquid when the wall 30 is flexed inwardly into the cavity formed by shell 28. This action drives any fluid in the bag outwardly through check valve 42 and conduit 38. Flexure of the wall outwardly of the shell removes the pressure against the exterior of the bag and enables fluid under pressure to flow into the bag along conduit 36 and through check valve 40. It may be appreciated that atmospheric pressure may be utilized to force the fluid into the bag during expansion thereof.

A base 50 is utilized to mount the pump and the drive mechanism to be hereinafter described. A U-shaped frame 52 is mounted on the base and extends upwardly therefrom. As is especially evident from FIG. 2, each upstanding leg of frame 52 is transversely L-shaped. Opposed, peripheral portions of wall 30 overlie respective legs of frame 52 when the pump is assembled for operation, and a pair of spring-loaded clamps 54 are utilized to maintain such peripheral portions in engagement with the legs of frame 52. As may clearly be seen in FIG. 2, the clamps 54 are transversely T-shaped, permitting the same to engage the opposed portions of the flange formed at the edge of shell 28 in mating engagement with the periphery of wall 30. Thus, the pump body is releasably maintained in place on the frame 52. Note that a ledge 56, extending outwardly from the bight of frame 52, forms a rest or seat for the lowermost portion of the pump body.

A block 58 mounted on base 50, has bearings 60 disposed thereon to receive the stem 48 and permit reciprocal movement thereof along its longitudinal axis. The driving of the stem is accomplished by a prime mover 62 which may be a linear actuator of the alternating current, induction motor type designed to reciprocate its armature or shaft 64 along the longitudinal axis thereof. Such actuators are conventional and commercially available components employing a stator wound so as to create a sweeping magnetic field which traverses the length of the stator when the motor is energized. For a given line connection, the field sweeps in one direction and, therefore, the direction of movement of shaft 64 may be controlled by reversing the line connections. Suitable control circuitry for an actuator of this type will be described hereinafter.

An assembly 66, including a member 68, an element 70 swingably attached to the member by a pin 72, and a rod 74 is slidably mounted on the base 50. The mounting of the assembly on the base is achieved by bearings 76 in the legs of a U-shaped bracket 78. The bight of the bracket 78 is rigid with block 58, the bracket being secured to the block by such means as cap screws 80.

Rod 74 is then received by bearing 76, thus permitting reciprocal movement of the rod along its longitudinal axis. A pair of arms 82 connect the opposite ends of rod 74 with the corresponding opposite ends of shaft 64. Each of the arms 82 may be joined with the corresponding ends of rod 74 and shaft 64 by any suitable means. Illustrated in FIG. 2 is a tapped hole along the longitudinal axis of shaft 64 for receiving a cap screw 84 to secure the arm thereto. Therefore, it may be appreciated that reciprocation of the shaft 64 by actuator 62 will effect movement of the assembly 66 therewith.

FIGS. 2 and 3 reveal the constructional features of the assembly 66. The member 68 is formed preferably from a sheet of metal bent to provide an apron 86 to increase the structural strength thereof. The arms 82 are integral with member 68 and formed by bending the plate stock of member 68 in the manner illustrated by FIGS. 2 and 3. It may be appreciated that the cuts in the plate stock needed to form the transverse edges of the apron 86 form the portions of arms 82 that connect to the opposed ends of shaft 64.

Element 70 is also formed from a plate of preferably metallic material. Element 70 has an elongated slot 88 therein presenting a guide 90. The plate forming element 70 is triangular in configuration and pointed at end 92 thereof. A slot 94 in member 68 receives a fastener (such as a bolt, nut and lock washer assembly) which is manually operable by rotating a knurled knob 96. The fastener extends through the end 92 of element 70. Thus, element 70 may be rotated about pin 72 through an angle defined by the ends of slot 94. This allows the angle formed by the rectilinear path of travel of assembly 66 and the longitudinal axis of slot 88 to be varied by the operator to control the length of the stroke of stem 48. A scale 98 on member 68 gives an indication of the pumping rate of the pump for a given setting. Both the knob 96 and the scale 98 are accessible by the operator through the access door 12.

A portion of member 68 is cut away to afford clearance of the slot 88 in element 70. This is to facilitate the connection of the end of stem 48 to the slot by such means as a roller 100 on a pin 102. The pin extends through the bifurcations at the end of stem 48 connecting with element 70 and the roller 100 rides longitudinally along the slot 88 as the assembly 66 is reciprocated.

In FIG. 2 a rheostat 104 (the rheostat may be mounted to either base 50 or case 10, knob 22 being secured to the shaft of the rheostat when case 10 is in place), a capacitor 106 and a cycle controller 108 are shown along with the On-Off switch 24. These electrical components are also shown in the schematic diagrams of FIGS. 6 to 8 inclusive.

Referring first to FIG. 6, the actuator 62 in the form of a linear motor as above described is shown with circuitry suitable for operating the motor. The On-Off switch 24 serves as the main switch to close the power circuit from the motor to a single phase, alternating current supply. The rheostat 104 is series connected between one side of the line and the linear motor and serves to adjust the level of the voltage applied to the motor. The cycle controller 108 comprises a timing motor 110 coupled with a reversing switch 112. Switch 112 is a single pole, double throw switch connected in the power circuit so as to alternately place leads 114 and 116 from the motor in electrical connection with lead 118 from the rheostat 104. It may be seen from FIG. 6 that the timing motor 110 of the cycle controller is connected in parallel with the linear motor but through main switch 24 so that its energization is controlled thereby.

As above described, the linear motor 62 is of the type wherein the reversal of the leads to the stator of the motor causes a corresponding reversal of the sweeping magnetic field and hence a reversal in the direction of the actuation of the armature. Therefore, the direction of movement of armature 64 is dependent on the position of reversing switch 112, current flow in lead 114 producing motion of armature 64 in a direction opposite to that produced by the flow of current in lead 116. A capacitor 120 is connected across leads 114 and 116 to provide a change in capacitive shifting during reversal of the motor.

The timing motor 110 may be a synchronous motor and the reversing switch 112 may be a pair of revolving switches coupled with the armature of the synchronous motor. It may be appreciated that such an arrangement will produce a reversal in the magnetic field of the stator of the motor at predetermined time intervals, depending on the speed of revolution of the rotor of the synchronous motor. Therefore, it is necessary to provide a means of assuring that the stroke of the armature 64 will be maintained constant for all loads placed thereon. Adjustment of rheostat 104 effects this function because the voltage applied to the motor may be increased or decreased corresponding to a heavier or lighter load so that the length of the stroke of the reciprocating armature 64 will remain unchanged.

The full operation of the instant invention will now be

described. A sanitary bag 34 and pump body 26 are placed on the ledge 56 against frame 52. The T-slot 47 in the end of stud 46 is then fitted in the mating tongue 49 extending from the end of stem 48 and the pumping unit clamped in place by clamps 54. The T-slot and tongue permit rapid and simple connection and disconnection of stud 46 and stem 48 and, in conjunction with spring-loaded clamps 54, facilitate rapid coupling of the pumping unit with the drive mechanism. It should be noted at this juncture that if it is not desired that the pump body 26 be of one-piece construction, and the bag 34 and fluid 32 be sealed therein, an inlet may be provided in body 26 to facilitate the adding of the liquid to the body. The inlet and outlet conduits 36 and 38 are then connected to the external fluid circuit and the operation of the pump may commence. By opening the access door 12, the operator may select the desired pumping rate by sliding the pointer 92 along slot 94 until the desired point on scale 98 is reached, at which time knob 96 may be tightened and the element 70 thus secured to member 68. Upon connecting motor 62 to the appropriate source and placing switch 24 in the "On" position, the stem 48 will then be caused to reciprocate and the wall or diaphragm 30 flexed against and away from the liquid 32.

An indicator 122 on member 68 (shown in FIG. 2) then permits the operator to visually monitor the stroke of assembly 66 through window 14 in the case 10. The space between the pointers 16 and 18 in the window represents the length of travel of the assembly 66 during reciprocation thereof. Prior to energization of motor 62, the indicator 122 will be in alignment with pointer 18. By viewing the movement of indicator 122 through window 14, the operator determines whether or not indicator 122 is in alignment with pointer 16 at the end of the path of travel of assembly 66. If the indicator and pointer 16 do not line up, the knob 22 controlling rheostat 104 is adjusted until proper alignment is effected. The operator is then assured that the pumping rate of the pump will correspond to the setting on the scale 98.

Referring now to FIG. 7, an alternate control diagram is shown that may be utilized to control the motor 62. The system of FIG. 7 shows an anticipated control sequence wherein the duration of the stroke of armature 64 is varied, thereby requiring that the power for each direction of stroke be varied accordingly in order to maintain constant the length of the stroke in either direction. To move the armature through the same distance in either direction in a shorter or longer time interval, an increase or decrease in power, respectively, is required. Therefore, a pair of rheostats 104a and 104b is employed.

FIG. 8 illustrates another alternate control system. This system shows a simple means of controlling the motor 62 where variations in load are at a minimum. In FIG. 8 a pair of single pole, single throw limit switches 124 are disposed at opposed ends of the path of travel of armature 64 and are mechanically interconnected by coupling means 126. Each of the switches 124 is of the type such that it will remain closed upon closure thereof by physical contact with the armature. Coupling means 126 permits only one switch to be closed at a given time.

Therefore, upon being actuated by the armature 64, the switch 124 so actuated, and the operation of coupling means 126, effects reversal of the motor.

Having thus described the invention, what is claimed 5 as new and desired to be secured by Letters Patent is:

1. In a pump:

a rigid shell and a flexible diaphragm extending across the edge of the shell forming a hollow body adapted to contain a substantially incompressible liquid; a flexible bag in said body provided with an inlet conduit and an outlet conduit extending through the shell to the exterior thereof, there being a check valve in each of said conduits, said liquid completely filling the body exteriorly of the bag;

a reciprocable member connected with said diaphragm and extending away from said body; and

means operably coupled with said member for reciprocating the latter to flex the diaphragm against and away from said liquid to collapse and expand the bag, whereby to pump a fluid into and out of the latter.

2. In a pump:

a hollow body adapted to maintain a substantially incompressible fluid therein, said body having a relatively rigid wall and a flexible wall spaced from and in opposed relation to a portion of the rigid wall;

a hollow, flexible bag in said body between said walls within said fluid and provided with inlet and outlet conduits extending through the body to the exterior of the latter; and

means for flexing said flexible wall toward and away from said portion of the rigid wall to collapse and expand the bag, whereby to pump material into and out of the bag, the fluid being solely confined within and completely filling the body exteriorly of the bag.

3. The invention of claim 2, wherein is provided a support for said body, and means on the support for releasably clamping the rigid wall and the flexible wall together to provide a seal therebetween.

4. The invention of claim 3, wherein said rigid wall comprises a shell having a continuous edge defining an opening in the shell, the latter being provided with an outwardly extending flange at said edge, said clamping means being engageable with said flange to releasably clamp said flexible wall between the flange and the support.
